OIL PRESSURE SAFETY CONTROL

Charles R. Neeson, Oakwood, Ohio, assignor to
Chrysler Corporation, Highland Park, Mich., a
corporation of Delaware

Application March 20, 1946, Serial No. 655,874

8 Claims. (Cl. 230—206)

1

My present invention relates to an improvement in control systems for a pressure lubricated mechanism such as refrigerant compressors, air compressors, stationary engines and the like. The invention is of particular utility in connection with a refrigerating or air conditioning system but in its broader aspects is applicable to any pressure lubricated mechanism.

The object of the present invention is to provide a control system for operating a motor starting switch or similar device for applying current to an electric motor driving a refrigerant compressor or like machine. The control system comprises means for disconnecting the source of current upon failure of the lubrication system.

Specifically, my invention comprises means including a pressure responsive device for closing an open switch in the control circuit, said switch being in parallel with a second switch normally in closed position to provide a starting circuit. The pressure responsive switch is normally in open position when the compressor is at rest and is closed when the compressor is operating and the oil pressure system is functioning satisfactorily. The first switch is associated with means for opening the switch a time interval after the second switch has closed, and further means for latching it in open position if the first switch is opened during operation of the compressor, which would be an indication of oil pressure failure. More specifically, the pressure responsive device comprises a diaphragm having means to apply the pressure of the lubrication system against one side and means for applying the pressure of the compressor crankcase against the opposite side, the crankcase pressure being operative to open the switch when the lubrication system is not functioning and having insufficient effect to open the switch if the lubrication system is functioning normally.

The objects and nature of the present invention will be more fully understood from the following specification taken in connection with the accompanying drawings wherein like numerals refer to like parts throughout.

In the drawings, Fig. 1 discloses a schematically illustrated refrigerating system having a simplified control circuit in which is incorporated the present invention, and Fig. 2 is a partial view of a modified form of control circuit.

The invention is shown as applied to a refrigerant compressor 10 having a piston 11 which compresses gas entering the cylinder space from a suction inlet 12 and discharges the compressed gas into a discharge head 13. Details of a suit-

able form of refrigerant compressor may be ascertained from my prior Patent No. 2,185,473 dated January 2, 1940, but any form of compressing device or other refrigerating mechanism

5 may have the present invention applied thereto. A refrigerating system is shown comprising a condenser 15 in which the compressed refrigerant is cooled and an expander 16 receiving refrigerant through an expansion valve 17 under control of a superheat bulb 18 in accordance with known practices. A feature of the preferred type of compressor is that the expanded gas entering the suction inlet 12 may also enter the crankcase space 20 of the compressor through a hole 21, for reasons more fully set forth in my prior Patents No. 2,185,743 dated January 2, 1940 and No. 2,204,510 dated January 11, 1940. The pressure existing in the crankcase 20 therefore fluctuates from a high pressure when the system is 10 at rest to a low pressure when the system is functioning, but in either case the pressure is a substantially steady pressure and varies from high to low when the system commences or from low to high when the system comes to rest at a fairly 15 smooth rate depending upon the size of the hole 21.

The compressor is controlled by a control system of which the basic elements are herein disclosed. Details of a control system not essential 20 to the present invention may be ascertained from any prior Patent No. 2,247,449 of July 1, 1941. As herein disclosed the compressor driving motor 25 is supplied with current through a manual switch 26 and an automatic, motor starting switch 27 operated by a solenoid 28. The solenoid 28 is placed in a control circuit deriving a reduced voltage from a transformer 29 having its primary winding in a single phase branch of the main current and in parallel with a blower motor 30 25 controlled by a manual switch 31, the blower motor being provided in a forced draft air conditioning system or the like. The solenoid 28 is also in series with the usual controls such as compressor motor overload switches 32 and 33, 30 a high pressure cut-out 34, a suction pressure cut-out 35, a manual switch 36 and a thermostatic switch 37. As illustrated the switch 34 is 35 controlled by a diaphragm motor 40 subject to the pressure of the discharge head 13, the switch 35 is controlled by a diaphragm motor 41 subject to the pressure in the suction inlet 12 and the switch 37 is controlled by a diaphragm motor 42 operated by the pressure of gas or liquid enclosed within a sensing device 43 positioned 40 within the refrigerated space or in the air con-

ditioning duct system. As will be readily apparent to those skilled in the art the switches 32, 33, 34 and 35 will normally be closed and will only open if an abnormal condition occurs requiring attention of the operator or at least requiring that the compressor cease operating, thus, the switch 27 will be closed if pushbutton 36 is closed when thermostatic switch 37 is closed, indicating that cooling is required. The subject of the present invention comprises further switches which must be satisfied before the switch 27 can be closed.

As seen in Fig. 1 the present invention comprises a first switch 50 in series with the others and including a bimetallic bar 51. In parallel with the switch 50 is a switch 52 which is normally open when the system is at rest. Switch 52 is operated by a rod 53 attached to a diaphragm 54 in a diaphragm motor 55. The space above the diaphragm 54 is supplied with oil from the pressure lubricating system through an inlet 56. As illustrated the pressure lubricating system may comprise a compressor driven oil pump 60 operated by the compressor, details of such a device being disclosed in my above-mentioned prior patents. The space below the diaphragm 54 is connected by means of a tube 61 and inlet 62 to the crankcase space 20. The pressure lubrication system is of the normal type operating at a pressure such as 40 pounds per square inch. When the compressor is idle the pressure of the crankcase may be in the nature of 100 pounds per square inch, thus, when the compressor is idle a positive force is applied to the diaphragm to open switch 52 even though there may be residual pressure in the space above the diaphragm. When the compressor is in operation and the pressure lubrication system is functioning normally there is a greater operative force above the diaphragm tending to close switch 52. Normally this greater pressure may occur within a very few number of reciprocations of the piston 11, but due to absorption of the refrigerant in the lubricant the pump may be slightly gasbound and the greater pressure may not be applied above the diaphragm until several seconds have elapsed after the compressor commences operation. In any event a starting circuit is supplied by the bimetallic bar 51 and soon thereafter a holding circuit is completed by the closing of switch 52.

In accordance with the present invention it is desired that the compressor cease operating if the oil pressure is below a predetermined minimum sufficient for lubrication purposes. To this end the upward thrust of the crankcase pressure which, when the compressor is operating may be in the nature of 5 pounds per square inch, or even negative pressure, is aided by a spring 63 of sufficient strength to overcome a predetermined minimum low oil pressure above the diaphragm even when the downward thrust of insufficient oil pressure is aided by a slight vacuum below the diaphragm. The spring 63 is so designed as to hold switch 52 in open position unless the oil pressure is satisfactory. In order to make certain that the diaphragm device 55 will take over control after the compressor starts operating with satisfactory oil pressure there is provided means to open the normally closed switch 50 a time interval after the compressor commences operation. This means comprises a resistance heater 64 placed in series with the other controls and located adjacent the bimetallic bar 51. The heater will cause warping of the element 51 a predetermined time after current commences to flow

through the control circuit. If the refrigeration system is in proper order the warping of element 51 will not disrupt the control circuit since switch 52 is in parallel therewith. However, if any of the switches 32, 33, 34, 35, 36 or 37 are opened current will cease flowing through the control circuit, switch 27 will open, the compressor will stop, the oil pressure will drop, and switch 52 will open. Soon thereafter element 51 will have cooled and closed switch 50 to set the system in readiness for the next operation.

The foregoing is satisfactory and sufficient for compressor control under the conditions stated. If, however, all of the switches 32, 33, 34, 35, 36 and 37 remain closed while switch 50 is open, and under such circumstances insufficient oil pressure causes switch 52 to open, I provide means to lock switch 50 open thereby preventing re-operation of the compressor until a service man corrects the faulty lubrication system. This means comprises a solenoid 65 in parallel with switches 50 and 52. The solenoid comprises an operating rod attached to a bell crank 66 having a free end adapted to contact the element 51 and warp it out of normal position, or if the element 51 has been previously warped by the heat of resistance 64 to lock it in the open position. Since switches 50 and 52 are open all of the current flowing through the control circuit will flow through the solenoid 65 and maintain the locking device in the lockout position. The electrical characteristics of solenoid 65 may be designated as being of the high resistance type, or in other words the solenoid 65 is so designed with respect to the solenoid 28 that solenoid 28 will have insufficient flux to hold the motor starting switch 27 in closed position when current flows through solenoid 65. Therefore, the compressor will stop when current flows through solenoid 65 even though a closed circuit is thus provided. Since this circumstance will arise when the manual switch 36 is closed no further action is possible until an operator arrives to correct the faulty lubrication system; in other words, since no current is flowing to motor 25 switches 32 and 33 will remain closed, since the compressor is at rest the refrigeration system will tend to balance and there will be no excessive reduction of head pressure to open switch 34 or excessive reduction of suction pressure to open switch 35, and switch 37 will remain closed since the temperature will rise due to failure of refrigeration. When an operator arrives and opens switch 36 the crank 65, either by automatic means such as a spring (not shown) or manually, will be caused to assume inoperative position and switch 50 will close but no harm will be done since a serviceman will be present to correct the cause of insufficient oil pressure.

In Fig. 2 I have illustrated a modified form of the invention in which switch 50 is operated by a delayed action solenoid 70 placed in the same position in the circuit as the resistance 64. Switch 50 is urged to closed position by a spring 71 and is caused to open after a short time interval by the magnetic buildup of coil 70. Switch 52 is operated by the rod 53 extending from the diaphragm device as previously described, but in this instance solenoid 65 operates a block or cam 72 cooperating with a block or cam 73 mounted on a rod 74 extending to switch 50. If switch 52 opens after switch 50 has been opened in this modification the block 72 is urged into contact with block 73 and switch 50 is held in open position.

Other forms of time delay devices and switch lockout devices will be readily apparent to others skilled in the arts pertaining thereto and I do not intend to be limited to the types herein disclosed. All such modifications as perform the functions herein disclosed are deemed to be a part of my invention.

It will be readily apparent to those skilled in the art of refrigeration that the pressure in suction inlet 12 might be applied to the diaphragm device, but I prefer the crankcase pressure since suction pressure is usually fluctuating. It will also be apparent that the present invention may be applied to an air compressor, or to an internal combustion engine or the like. In such cases the pipe 61 may be omitted since crankcase pressure will be normal air pressure or close to it. In the case of an internal combustion engine or the like the control circuit may include a starting motor and an ignition cut-off in case of oil pressure failure.

Having illustrated and described preferred embodiments of the invention I now claim as my invention the following:

1. In a refrigerant compressor mechanism having a pressure lubrication system; a control system for said mechanism comprising a normally closed switch, a normally open switch in parallel therewith, a high resistance induction coil in parallel with said switches, a time-delay device for opening said normally closed switch a short time after current flows through the control system, a pressure-responsive device for closing said normally open switch as long as sufficient pressure exists in said lubrication system, and means controlled by said high resistance coil to lock said normally closed switch in open position if the pressure falls below a predetermined minimum.

2. In a pressure-lubricated mechanism; a control circuit comprising a normally closed switch, a normally open switch in parallel therewith, means responsive to the pressure of the lubricant for closing said normally open switch, means in series with said switches and responsive to the flow of current through said circuit to open said normally closed switch a time interval after current commences flowing, and electrically controlled means operative upon both switches being simultaneously in open position to lock said normally closed switch in open position.

3. In a pressure-lubricated compressor mechanism having a motor starter switch; a control circuit comprising a normally open switch, a normally closed switch in parallel therewith, a first induction coil in parallel with said switches, a second induction coil in series with said switches and said first coil, means in series with said switches and said induction coils and responsive to the flow of current through said circuit to open said normally closed switch an interval of time after current commences to flow, means responsive to pressure of the lubricant to close said normally open switch, and means associated with said first induction coil and operative upon simultaneous opening of both said switches and resulting flow of current through said first induction coil to hold said normally closed switch in open position, said second induction coil being adapted to operate said motor starter switch or similar device when either of said switches is closed but having such characteristics, electrically, with respect to said first induction coil, as to be inoperative when both said switches are open and current flows through said first induction coil.

4. In an oil pressure safety control for a pressure-lubricated refrigerant compressor; a control circuit including a pair of switches in parallel, one normally open and the other normally closed, time-delay means in series with said switches and adapted to open said normally closed switch a short interval of time after current commences to flow through said circuit, lubricant pressure responsive means to close said normally open switch, means to oppose said lubricant pressure responsive means by the compressor crankcase pressure to reopen said normally open switch if the pressure of the lubricant falls below a predetermined minimum, a locking device, and a shunt around said switches including electrically controlled means operative upon said locking device to lock said normally closed switch in open position if said normally open switch is reopened while said normally closed switch is open.
- 10 5. In a refrigerant compressor having a compressor-driven oil pump and connected pressure lubrication system; a control circuit including a switch, a diaphragm device for operating said switch, means connecting said diaphragm device to said pressure lubrication system for closing said switch after the compressor starts operation, means connecting said diaphragm device to the crankcase of said compressor for operation in the opposite direction if the oil pressure falls below a predetermined minimum, a second switch in parallel with said first switch having a bimetal contact and adapted to be in closed position when said control circuit is deenergized, and time-delay electrical heating means in series with
- 15 30 35 said switches and adapted to warp said bimetal contact to open said second switch a short interval of time after said first switch is closed by the action of said diaphragm device.
6. In a refrigerant compressor having a compressor-driven oil pump and connected pressure lubrication system; a control circuit including a first switch, a diaphragm device for operating said switch, means connecting said diaphragm device to said pressure lubrication system for closing said switch after the compressor starts operation, means connecting said diaphragm device to the crankcase of said compressor for operation in the opposite direction if the oil pressure falls below a predetermined minimum, a second switch is parallel with said first switch having a bimetal contact and adapted to be in closed position when said control circuit is deenergized under normal circumstances to thus complete a closed circuit for starting said compressor when energized, time-delay electrical heating means in series with said switches and adapted to warp said bimetal contact to open said second switch a short interval of time after said first switch is closed by the action of said diaphragm device, a shunt around both of said switches including a high resistance induction coil, and latching means energized thereby to lock said second switch in open position if said first switch thereafter opens.
- 40 45 55 60 65 70 75 7. In a refrigerant compressor having a compressor-driven oil pump and connected pressure lubrication system; a control circuit including a first switch, a diaphragm device for operating said switch, means connecting said diaphragm device to said pressure lubrication system for closing said switch after the compressor starts operation, means connecting said diaphragm device to the crankcase of said compressor for operation in the opposite direction if the oil pressure falls below a predetermined minimum, a

second switch in parallel with said first switch and adapted to be in closed position when said control circuit is deenergized under normal circumstances to thus complete a closed circuit for starting said compressor when energized, time-delay means in series with said switches to open said second switch a short interval of time after said first switch is closed by the action of said diaphragm device, a shunt around both of said switches including a high resistance induction coil, latching means energized by said high resistance induction coil thereby to lock said second switch in open position if said first switch thereafter opens, and resilient means urging said first switch toward open position at all times.

8. A control system for a refrigerant compressor having a compressor-driven oil pump and connected pressure lubrication system, comprising a control circuit including a first switch, a diaphragm device for operating said switch, means connecting said diaphragm device to said pressure lubrication system for closing said switch after the compressor starts operation, means connecting said diaphragm device to the crankcase of said compressor for operation in the opposite direction if the oil pressure falls below a predetermined minimum, a second switch in parallel

with said first switch and adapted to be in closed position when said control circuit is deenergized under normal circumstances to thus complete a closed circuit for starting said compressor when energized, time-delay means to open said second switch a short interval of time after said first switch is closed by the action of said diaphragm device, a shunt around both of said switches including a high resistance induction coil, latching means energized thereby to lock said second switch in open position if said first switch thereafter opens, and resilient means urging said second switch toward closed position, said latching means comprising a movable part rendering said resilient means ineffective.
